Primary Examiner — John Windmuller(74) *Attorney, Agent, or Firm* — Jordan One; Greenberg Traurig, LLP(57) **CLAIM**

I claim the ornamental design for an enclosed gutter clip, as shown and described.

DESCRIPTION

FIG. 1 is a front perspective view of my enclosed gutter clip;
 FIG. 2 is a rear perspective view thereof;
 FIG. 3 is a left side elevation view thereof;
 FIG. 4 is a right side elevation view thereof;
 FIG. 5 is a rear elevation view thereof;
 FIG. 6 is a front elevation view thereof;
 FIG. 7 is a bottom plan view thereof; and,
 FIG. 8 is a top plan view thereof.
